DESIGN FOR A PHOTOGRAPHIC EXPOSURE CALCULATOR

Hugh Alfred Wennerholm, Santa Monica, Calif.

Application August 22, 1939, Serial No. 86,828

Term of patent 7 years

To all whom it may concern:

Be it known that I, Hugh Alfred Wennerholm, a citizen of the United States, residing at Santa Monica, in the county of Los Angeles and State of California, have invented a new, original, and ornamental Design for a Photographic Exposure Calculator, of which the following is a specification, reference being had to the accompanying drawing, forming part thereof.

The figure is a plan view of a photographic exposure calculator, showing my new design. The design is of no appreciable thickness.

I claim:

The ornamental design for a photographic exposure calculator, as shown and described.

HUGH ALFRED WENNERHOLM.
